UNITED STATES PATENT OFFICE.

EUGENE R. CARICHOFF, OF SCHENECTADY, NEW YORK, ASSIGNOR TO GENERAL ELECTRIC COMPANY, A CORPORATION OF NEW YORK.

ELECTROMAGNETIC DEVICE.

Application filed December 18, 1922. Serial No. 607,576.

My invention relates to operating electromagnets and in particular to operating electromagnets for electric switches.

The invention has a particular application in electromagnetic switches which are used in systems of motor control in which the control of the electric motor is in response to the generated or counter-electromotive force of the motor, although the invention is not necessarily limited to such use. One of the difficulties encountered in controlling an electric motor in response to the generated or counter-electromotive force of the motor is that of compensating for variations in supply circuit potential. Another difficulty encountered arises from the fact that the heating of the coils of the electro-magnetic motor controlling switches causes the operation of the switches to vary. In my former Patent No. 867,476, dated October 1, 1907, I have disclosed and claimed broadly a motor control arrangement involving the use of the counter-electromotive force principle in which compensation is made for variations in line potential and for the heating of the switch coils, and in my Patent No. 1,311,754, dated July 29, 1919, I have disclosed and claimed an improved arrangement which involves the use of electromagnetic switches of the lock-out type which are designed to hold open when the current is high and to close and be magnetically held closed when the effective magnetic flux of the switch structure has dropped to a predetermined value. The arrangement disclosed in my said Patent No. 1,311,754, while entirely operative and practical, leaves something to be desired from the standpoint of manufacture of the switch, because of the fact that the magnetic flux set up by the coil which tends to hold the switch in the open position is interlinked with the magnetic flux of the coil which tends to close the switch. By reason of the fact that the flux across the closing gap of the switch is the controlling influence in the operation of the switch, variations in the closing flux or variations in the holding-open flux render the switch uncertain in operation and also render it difficult to adapt a single switch to various applications.

The present invention has for one of its objects the improvement of the operating electromagnets for the electric switches disclosed in my aforesaid prior patents. An-

other of the objects of the invention is to provide an improved electromagnetic device in which two substantially independent magnetic forces are set up, one force tending to actuate the magnetic movable element or member of the electromagnet and the other force acting in opposition thereto to hold the said member from actuating, with a substantially constant difference in the value of the magnetic forces while the ratio of the voltages applied to the separate windings of the electromagnets varies. Another object of the invention is to provide an improved electromagnetic device in which the separate magnetic forces vary at different rates when the voltages applied to the windings of the electromagnets vary at the same rate.

In carrying the invention into effect, I provide an operating electromagnetic device for an electric switch which has substantially independent electromagnets which together control a single magnetic movable member for operating a switch member. Each of the electromagnets has a substantially independent magnetic structure, so that a variation in the flux set up by one of the magnets has substantially no effect on the magnetic flux of the other electromagnet. When used in a system of motor control for starting a motor in accordance with a compensated counter-electromotive force principle, the one electromagnet may have its winding connected across the supply circuit so as to provide a holding-open force which opposes the actuating force of the other electromagnet which has its winding connected to be energized in accordance with the counter-electromotive force of the motor. The magnetic structures of the opposing and the actuating electromagnets are such that there are two separate magnetic forces set up with respect to the switch member which have a substantially constant difference in value while the voltages applied to the windings of the electromagnets vary in value by a substantially constant difference, and the magnetic forces vary at a different rate when the voltages applied to the windings vary at the same rate. The arrangement is such that by reason of the electromagnets having substantially independent electromagnetic circuits, the effect of the closing or actuating electromagnet may be varied independently of the holding-open or op-

posing electromagnet. The operating electromagnetic device lends itself to large scale manufacture by reason of the fact that the same may be readily adjusted to meet 5 a number of different conditions.

The arrangement is such that when the switch is used in controlling an electric motor in accordance with the compensated counter-electromotive force principle, if the 10 line voltage varies, it will have substantially no effect on the operation of the switch in so far as the proper control of the electric motor is concerned. In other words, the switch inherently compensates for changes 15 of the supply circuit potential and for the heating of the switch coils, so that within the operating range of voltages of the switch, the switch will be operated by the actuating electromagnet when the voltage 20 applied to the actuating electromagnet bears a certain relation to the voltage applied to the opposing electromagnet. Thus, if it is desired that the switch shall close when the line voltage is 100 and the motor counter- 25 electromotive force is 90 volts, if the line voltage drop to 90, the switch will close when the motor counter-electromotive force is 80 volts.

For a better understanding of my invention, reference is had to the accompanying drawings wherein I have shown an embodiment of my invention in concrete form for purposes of illustration, and in which Fig. 1 is a side view of an electromagnetic switch 30 constructed in accordance with my invention; Fig. 2 is a plan view of the same; Fig. 3 is a very simplified motor control diagram employing the electromagnetic switch of the invention; Fig. 4 is a curve showing the relation between the relative pull and the relative excitation of the windings of the switch electromagnets; and Fig. 5 is a similar curve sheet showing a part of the curves of Fig. 4 to an enlarged scale, for the purpose of 45 showing more clearly the manner in which there is a substantial constant difference in value of the magnetic forces exerted by the electromagnets upon the switch member while the ratio of the voltages applied to 50 the windings of the electromagnets varies, or while the voltages applied to the windings of the electromagnets vary in value by a substantially constant difference.

Referring to the drawings, the electromagnetic switch is provided with two substantially independent electromagnets 10 and 11 which cooperate to control the single movable switch member 12. The electromagnet 10 has a magnetic structure which 55 is practically independent of the magnetic structure of the electromagnet 11, and both of these electromagnets control the pivotally mounted magnetic movable member or armature 13 to which the switch member 12 is attached. The armature 13 is biased to

such position that the switch member 12 is normally out of engagement with the stationary contact 14, so that the switch is normally in the open position. The winding of the electromagnet 11 is adapted to be energized in accordance with the voltage of the source of supply to hold the switch in the open position against the action of the electromagnet 10 on the other side of the pivotal support for the armature 13 tending to close the switch. The winding of the electromagnet 10 is adapted to be energized responsively to the counter-electromotive force of the motor, and when the switch is used in controlling the starting of an electric motor, the lower end of the armature 13 will be attracted by the electromagnet 11 to hold the switch in the open position until the counter-electromotive force generated by the motor armature has increased to such 85 a value that the pull of the electromagnet 10, which is provided with a greater number of turns of the winding than the winding 11, overcomes the pull of the electromagnet 11 and thereby causes the switch to close 90 at the proper interval in the acceleration of the motor.

The various parts of the electromagnetic switch are mounted upon the insulating base 23, and the electromagnet 11 has a stationary core 15 with which the adjustable armature 16 carried by the lower end of the armature 13 is adapted to make engagement. The electromagnet 10 has a magnetic structure comprising the core 17, the strap 18 and the magnetic member 19 which serves as a stop for the armature 13 in cooperation with the strap 18. The armature 13 is pivotally supported from the strap 18. The lines of flux set up by the electromagnet 11 will be substantially independent of the lines of flux set up by the electromagnet 10, so that the pull of each electromagnet is not influenced by variations of magnetic flux in the other electromagnet due to the interlinking of 100 magnetic fluxes as in the electromagnetic switch of my Patent No. 1,311,754. The armature 16 may be adjusted with respect to the core 15 so as to vary the air gap between the core 17 and the upper end of the armature 13 when the switch is in the open position, thereby varying the value of the counter-electromotive force of the motor at which the switch will be operated to close. 115

The operation of my invention will be understood from a description of the operation of the motor control arrangement shown very diagrammatically in Fig. 3. In order to start the electric motor having an armature A and field F, the pilot switch 20 will be closed to energize the line contactor 21 and thereby connect the motor to the source of supply 22 with the starting resistors R¹, R² and R³ included in the motor armature circuit. The closing of the pilot switch 20 120

connects the windings 11^a, 11^b and 11^c in series with the winding of the contactor 21 across the supply circuit, and the lower ends of the armatures 13^a, 13^b and 13^c are attracted to move their respective switch members farther away from the closed position. The closing of the line contactor 21 also energizes the windings of the closing electromagnets 10^a, 10^b and 10^c in series relation across the motor armature so as to be energized responsively to the counter-electromotive force of the motor. These windings will have a greater number of turns than the windings of the holding-open electromagnets, so that when the counter-electromotive force of the motor has increased to a predetermined value due to the speeding up of the motor, the pull of the electromagnet 10^a will predominate over the pull of the electromagnet 11^a and the switch will close to short circuit the resistor R¹. The resistors R² and R³ will be successively short circuited by their respective switches responsively to the speeding up of the motor in a manner which will be well understood by those skilled in the art from the previous description.

The electromagnetic accelerating switches may be independently adjusted by adjusting their armatures 16^a, 16^b and 16^c with respect to the armatures 13^a, 13^b and 13^c respectively, so that the resistor R¹ will be short circuited at one value of the counter-electromotive force, the resistor R² at a higher value of counter-electromotive force, and the resistor R³ at a still higher value of counter-electromotive force of the motor.

If the line voltage varies above or below normal, the closing of the accelerating switches will be correspondingly effected. For instance, if the voltage should be below normal, the flux due to the winding 11 will be a corresponding value less than normal, and the flux due to the winding 10 will also be a correspondingly smaller value, so that when the voltage is lowered the switch will close at a lower value of counter-electromotive force, and if the voltage is above normal the switch will close at a correspondingly higher value of counter-electromotive force. Thus, by reference to Fig. 5, it will be seen that the magnetic circuits of the electromagnets are such that there will be a substantially constant difference in the separate magnetic fluxes set up by the two electromagnets while the applied voltages simultaneously vary. The magnetic forces thus vary at a different rate while the exciting currents in the coils vary at the same rate. The switch will therefore always close within the operating range of voltages when there is a predetermined difference between the voltages applied to the two coils of the switch. Thus, if it is desired to have the switch close when the line voltage is 100 volts and the motor counter-electromotive force 90 volts, 100 volts

being the normal line voltage, if the line voltage drop to 90 volts, the switch will close when the counter-electromotive force is 80 volts, or if the line voltage rises to 110 volts, the switch will close when the counter-electromotive force is 100 volts. The ratios of 100 to 90, 90 to 80 and 110 to 100 are all different but the switch inherently takes care of this condition.

Changes of temperature have substantial- 75 ly no effect on the operation of the switch because of the fact that since both coils are heated or cooled at substantially the same rate, the change in the pull of one electromagnet will be offset by the change in the 80 pull of the other electromagnet. In other words, the switch will close at substantially the same value of counter-electromotive force whether the winding 10 is cold or hot, since the winding 11 will be in a similar condition. 85

By reason of the fact that the calibration of the switch may be very readily changed by simply adjusting the armature 16 in position to thereby vary the air gap for the upper end of the armature 13 with respect to the core 17, the switch can readily be adapted to meet a great number of various applications. Furthermore, the ratio of the ampere turns of the windings 10 and 11 may 90 be changed as desired in order to adapt the switch to various applications, and no account need be taken of the fact that the magnetic flux set up by one electromagnet is interlinked with the magnetic flux set up by the other electromagnet. Where it is necessary to take into account the interlinking of the magnetic fluxes of the two electromagnets, it is difficult to readily design a switch to give certain desired operating characteristics. In my present invention, by reason of the fact that the magnetic fluxes set up by the two electromagnets are substantially independent of each other, the effect of each electromagnet on the switch 100 member can be independently determined if desired without relation to the effect of the other electromagnet on the switch member. In other words, the switch can be readily designed by calculation and a few simple experiments rather than by a cut and try method. 105

It will be observed that the switch is positively held open by an independent electromagnet which is directly energized from the supply circuit, thereby insuring that the switch will always be in the open position at starting and be held open positively until the counter-electromotive force of the motor increases. 110

What I claim as new and desire to secure by Letters Patent of the United States, is,—

A motor controlling electromagnetic device, comprising a magnetic movable member normally in one position, an electro- 120

magnet having a magnetic structure and a winding thereon for operating the said member to a second position, a second electromagnet having a magnetic structure and a winding thereon for holding the said member in the first position against the pull of the first electromagnet, the said second electromagnet having a path for the magnetic flux which is substantially independent of the 10 magnetic flux set up by the first electromagnet and the said windings and magnetic structures of the electromagnets being pro- portioned to set up two separate magnetic forces which are exerted on said member and which have a substantially constant difference in value while the voltages applied to the windings of the electromagnets vary in value by a substantially constant difference and which vary at a different rate while the voltages applied to said windings vary at 15 the same rate.

In witness whereof, I have hereunto set my hand this 15th day of December, 1922.

EUGENE R. CARICHOFF.
